UNITED STATES PATENT OFFICE

GEORGE F. MATTESON, OF ROCKYHILL, CONNECTICUT, ASSIGNOR TO THE ABBOTT BALL COMPANY, OF ELMWOOD, CONNECTICUT, A CORPORATION OF CONNECTICUT

FEEDING MECHANISM

Application filed December 20, 1928. Serial No. 327,376.

My invention relates to that class of mechanisms that are employed for feeding articles for various purposes, in one of its forms it being particularly advantageous 5 for feeding spherical or similarly shaped articles, and an object of my invention, among others, is the production of a feeding mechanism that shall be capable of handling articles in a rapid and efficient manner.

10 One form of a feeding mechanism embodying my invention and in the construction and use of which the objects herein set out, as well as others, may be attained, is illustrated in the accompanying drawings 15 in which—

Figure 1 is a view in side elevation of my improved feeding mechanism, with parts being broken away to show construction.

Figure 2 is an edge view of the same.

20 Figure 3 is a view, scale enlarged, in vertical section on a plane passing through the axis of the rotary feeding member.

Figure 4 is a side view, to the same scale as Figure 3, with parts being broken away 25 to show construction.

Figure 5 is a detail view illustrating the manner of operation of the guiding table.

Figure 6 is a detail view illustrating the construction of the way for delivering articles to the forming member and on a plane denoted by the dotted line 6—6 of Figure 2.

Figure 7 is a top view of the table, delivery chute and way.

30 My improved feeding mechanism or device, while not limited in its use to handling articles of any special form or shape, is particularly adapted for use in manipulating articles of spherical or similar form. Furthermore, while it is not limited to the 35 feeding of articles for any particular purpose, yet, as I have found it especially applicable for handling balls or other round or substantially round objects in connection with grinding or other forming devices,

40 45 I have illustrated such mechanism in the drawings herein in which the numeral 6 indicates a case or housing shaped to enclose a feeding member 7 rotatably mounted in the case and formed with a chamber 8 50 to contain the articles to be fed. This feed-

ing member is substantially round as to a side view and is mounted preferably upon a horizontal axis in the case or housing 6 and upon rollers 9 rotatably mounted in bearings in the side walls of the case. The feeding 55 member rests upon the rollers that are separated sufficiently to cause said member to retain its place on the rollers, said member being driven by frictional contact with the rollers. In the structure herein shown there 60 is a pair of rollers located, one pair on the opposite side of a vertical plane through the axis of the rotating member from the other pair. Each pair of rollers includes a shaft having a worm wheel 10 secured thereto and 65 meshing with a worm 11, which worms are secured to or are formed as a part of a driving shaft 12 mounted in bearings on the side of the case or housing at the lower part thereof and driven as by means of a pulley 70 13 secured to said shaft.

The wall of the chamber 8 in the feeding member is formed with a series of pockets 14 extending crosswise of the feeding member and preferably diagonal to radial lines, 75 and as shown in Figure 4 of the drawings. A way 15 is supported with one end in the chamber 8 in the feeding member, said way extending out through a central opening 16 in the side of the case 6. The opposite and 80 lower end of said way is located in position to deliver the articles, as balls, to such location as may be desired.

This way consists of a base 17 having a series of substantially parallel grooves 18 85 forming paths along which the articles travel. A cover plate 19 is secured to the base to close the open sides of the grooves to retain the articles 20 therein.

90 In the illustration of use employed herein the articles of spherical or similar shape, in the present instance of metal, are delivered to a grinding or other forming disc 21 that is mounted to rotate in any suitable manner, not herein shown, and preferably on a horizontal axis, said disc having a series of grooves 22 concentrically arranged, and the grooves in the way 15 preferably correspond in number to those in the forming disc, so 95 that each groove in the way is constantly 100

delivering a stream of articles to the forming disc, to one of the grooves therein.

In the operation of forming spherical objects, and particularly metallic balls, it is 5 desirable, in order to obtain uniformity in size, to subject the balls to a series of operations by the forming disc, and further, to obtain this result in uniformity of size, it is important that each ball shall travel or be 10 operated upon in a different groove in the forming disc at each succeeding operation. To effect this result the feeding mechanism is arranged, first, to deliver the balls to the forming disc and then to collect them and 15 repeat the operation as many times as may be desired.

To this end I provide a scoop 23 in the form of a trough with one edge in contact with the disc 21 whereby the balls are 20 scooped from grooves 22 and are delivered by the trough into the chamber 8 in the feeding member, the trough extending inwardly through the opening 16 into said chamber, and as shown in Figure 3 of the 25 drawings.

The way 15 is provided with a comparatively wide mouth 24 located underneath the mouths of the pockets 14 when the latter are moved to the upper part of the chamber 8 in the feed member, and a table 25 is located in an inclined position to receive the balls from the pockets and guide them into the mouth 24, and as shown in Figure 4. The table is provided on its upper surface with 20 a series of grooves 26 preferably of the same number as and registering with those in the way 15.

As a ready means for removing the balls from the chamber 8, and especially after an operation of forming them has been completed, I locate the table 25 as a cover for the mouth of a delivery chute 27 also having a comparatively wide mouth at its upper end and terminating a tube 28 at its lower end, which tube projects outwardly through an eye 29 in the side of the housing 6. The table is mounted on pivots 30 in opposite sides of the delivery chute and it has 25 a counterweight 31 projecting underneath it at one edge. A wire or cord 32 is secured at one end to the underside of the table 25 and projects with its opposite end out of the lower end of the tube 28 to serve as a means 30 for tipping the table, as into the position shown in Figure 5, to deliver the articles to the tube 28, the counterweight acting to return the table to its normal position, as shown in Figure 4, when pull upon the cord 35 is released.

The chamber 8 may be supplied with a proper amount of articles in any manner desired. For instance, a portable chute 35 may be inserted through the eye 29 in the case and through a registering hole 33 in

the member 7. Opposite the hole 33 the member 7 has a hole registering with the opening 16, this hole 34 having a flange 35 extending into the opening 16 and as shown in Figure 3 of the drawings. 70

From this disclosure it is to be observed that the balls or other articles are placed in the feeding member in a disorderly condition and are delivered therefrom to the way 15 where they are deposited in an orderly manner. This order is preserved in the travel of the articles along the way 15, into and around the forming disc 21 until they reach the scoop 23. Here the articles are collected and are promptly mixed and disarranged by the scoop by which they are delivered to the member 7 in this disordered condition and by which member 7 they are further disarranged for a repeated delivery to the way 15, the operation being thus repeated for such number of operations as may be desired to effect a proper formation of the articles. 80

It is a practical impossibility to obtain the same result on all balls formed in different grooves in the forming disc and, therefore, if each ball traveled in the same path at each operation, only those that traveled in the same paths would have the same form. By mixing the articles up and causing them to travel in different paths at successive operations a substantially and practically uniformity in shape is obtained for all of the articles. 90

In order to prevent an accumulation of articles in the mouth 24 of the way, I provide an overflow in the form of a slot 36 in the back of the way, approximately at the throat of the mouth 24 so that should the articles be delivered to any of the paths or grooves 18 faster than they are removed therefrom at the lower end, as soon as a path or groove is filled up to the slot 36, any accumulation thereafter will be discharged through said slot and fall into the bottom of the feeding member to be again taken up in the manner hereinbefore described. 100

It will be noted that the way provides for the travel of articles in different and separate paths after they are delivered into the mouth 24, in the particular arrangement herein shown a plate having grooves for travel of the articles being employed, but I contemplate other means and arrangements whereby the articles may be caused to travel in different paths, my invention not being limited to the exact construction herein shown. It will also be understood that arrangements other than the rolls and the friction drive for rotating the feeding member may be employed without departing from the spirit and intent of the invention. 110

In accordance with the provisions of the patent statutes I have described the principles of operation of my invention, together 120

with the device which I now consider to represent the best embodiment thereof; but I desire to have it understood that the device shown is only illustrative, and that the 5 invention may be carried out by other means and applied to uses other than those above set out.

I claim:

1. A feeding mechanism comprising a rotatably mounted feeding member having a chamber with an opening therefrom, pockets located in the wall of said chamber to pick up articles from the bottom thereof, a way extending into said chamber through said 10 opening and supported in a fixed position independent of the feeding member to receive articles as they fall from said pockets, said way having grooves forming paths, a table supported to receive articles from said 15 pockets and guide them into said way, and grooves formed in the surface of said table and registering with the grooves in said way and said table being shiftable to a position out of communication with the way.
2. A feeding mechanism comprising a rotatably mounted feeding member having a chamber with openings thereto from opposite sides of said chamber, pockets located in the wall of said chamber to pick up 20 articles from the bottom thereof, a way projecting through one of said openings into the chamber and supported in fixed position to receive articles as they fall from said pockets, a delivery chute projecting through 25 the other opening into said chamber to receive articles as they fall from said pockets, and means for delivering said articles either to said way or said delivery chute.
3. A feeding mechanism comprising a rotatably mounted feeding member having a chamber with an opening thereto, pockets formed in the wall of said chamber, a way extending into said chamber and fixedly positioned to receive articles as they fall from 30 said pockets, a delivery chute projecting into said chamber and fixedly positioned to receive articles as they fall from said pockets, and a table pivotally mounted to, in one position, guide articles into said way, and 35 when tipped to another position, to guide said articles into said delivery chute.

4. A feeding mechanism comprising a rotatably mounted feeding member having a chamber with an opening thereto, a way 40 suspended within said chamber to receive and deliver articles out of said chamber, a member to act upon said articles delivered from said way, means positioned to receive said articles from said member and conduct 45 them back to said chamber and controllable means at the receiving end of the way for delivery of the articles from said chamber at another point.

5. A feeding mechanism comprising a rotatably mounted feeding member having a 50

chamber therein, a way fixedly positioned to receive articles and conduct them from said chamber, a member to act upon said articles delivered thereto by said way, and a scoop positioned in the path of movement of 70 articles in said second named member to scoop up said articles and return them into said chamber and controllable means for finally delivering the articles from the chamber at another point.

6. A feeding mechanism comprising a rotatably mounted feeding member having a chamber, a way positioned to collect articles from said chamber and guide them therefrom, a member to act upon articles delivered from said chamber, means for collecting articles from said member to deliver them within said chamber, and means for finally conducting articles from said chamber.

7. A feeding mechanism comprising a rotatably mounted feeding member having a chamber to contain a supply of articles in the bottom thereof, means for rotating said member, pockets located in the wall of said chamber each to pick up articles from the bottom of the chamber and carry them upwardly therein, and a way projecting into said chamber with its inner end positioned to receive articles as they fall from said pockets, means to act upon the articles and return them to the chamber and controllable means for final removal of the articles from the chamber independently of the way.

8. A feeding mechanism comprising a case, a feeding member rotatably mounted in the case and comprising a peripherally closed chamber with pockets formed in the inner wall of said chamber and projecting inwardly, and a way projecting into the interior of said chamber and positioned to receive articles as they fall from said pockets, and said way having a cut-out portion permitting return to the chamber of excess articles received from said pockets.

9. A feeding mechanism comprising a case, a feeding member rotatably mounted in the case and comprising a peripherally closed chamber having pockets formed in the inner wall of said chamber and opening into the interior thereof, and a way projecting through the side of said chamber and positioned in the interior thereof and having grooves forming a plurality of parts to receive articles as they fall from either of said pockets, and said way having a cut-out portion permitting return to the chamber of excess articles received from said pockets.

10. A feeding mechanism comprising a rotatably mounted feeding member having a peripherally closed chamber with an opening in the axis of said chamber, means for rotating said member, pockets formed in the inner wall of said chamber and projecting thereinto, and a way projecting through

said opening into the interior of said chamber underlying said pockets to receive articles as they fall from either of said pockets, said way having a cut-out portion permitting return to the chamber of excess articles received from said pockets, and controllable means associated with the way for delivery of articles from the chamber independently of the way.

- 10 11. A feeding mechanism comprising a rotatably mounted feeding member having a peripherally closed chamber with an opening therefrom, means for rotating said chamber, pockets formed in the inner wall of said chamber and projecting thereinto and extending across the feeding member from side to side, and a way extending through said opening and supported within the interior of said chamber in a fixed position
- 15 therein said way having grooves located side by side for the reception of articles falling through space from each of said pockets into each of said grooves and controllable means associated with the way for delivery
- 20 of articles from the chamber independently of the way.

12. A feeding mechanism comprising a rotatably mounted feeding member having a peripherally closed chamber therein with
- 25 openings therefrom and with pockets formed in the inner wall of said chamber and opening thereinto, a way projecting through one of said openings and positioned within the interior of said chamber and supported in a
- 30 fixed position to receive articles as they fall directly from all of said pockets on to said way, means for guiding articles into the mouth of said way and controllable means associated with the way for delivery of articles from the chamber independently of the
- 35 way through the other opening.

GEORGE F. MATTESON.
